MOLD-FLASK SEPARATOR

Arnold H. Feldman, Chicago, Ill.

Application February 25, 1937, Serial No. 127,753

6 Claims. (Cl. 18—33)

This invention relates to a mold-flask separator, and is designed primarily for use in connection with a dental mold and flask which are used when curing or processing denture materials, but it is to be understood that a separator, in accordance with this invention, is to be employed in any connection for which it may be found applicable.

The object of the invention is to provide, in a manner as hereinafter set forth, means whereby a mold with a molded article therein may be expeditiously withdrawn from a flask without injury to the latter or to the article.

Further objects of the invention are to provide, in a manner as hereinafter set forth, a separator which will overcome the necessity of digging the plaster or investment away from the sides of a flask to free the mold; prevents any damage to molded article while removing the mold from the flask; overcomes the necessity of destroying the flask when removing the mold; overcomes the necessity of hammering the side of the flask in order to remove the mold; enables the use of the same flask for a period of years; permits of the flask being used indefinitely with as much accuracy as when the flask was first used; provides when used the saving in time and labor when separating the flask from a mold; provides for the expeditious separation of a mold from a flask; requires no special ability in the positioning relative to a flask; in no manner alters the form, size or shape of the molded article; has no chemical or physical effect upon the investing material; and will lessen the resistance or adherence of the investing material to the flask after the molded article has been cured or processed.

Further objects of the invention are to provide, in a manner as hereinafter set forth, a mold-flask separator which is simple in its construction, strong, durable, compact, readily installed with respect to a flask, thoroughly efficient in its use, prolonging the life of a flask, easily handled as it is of light weight, and comparatively inexpensive to manufacture.

To the above ends essentially and to others which may hereinafter appear, the invention consists of the novel construction, combination and arrangement of parts as will be more specifically referred to and are as illustrated in the accompanying drawing wherein is shown an embodiment of the invention, but it is to be understood that changes, variations and modifications may be resorted to which fall within the scope of the invention as claimed.

In the drawing:

Figure 1 is a top plan view of a flask having its top or closure plate removed, the flask containing a mold and showing the adaptation with the flask and mold of the separator and with the latter being in extended position relative to the flask,

Figure 2 is a view similar to Figure 1 with the separator in anchored or non-extended position,

Figure 3 is a cross sectional view of a flask with its top or closure plate removed, the flask containing a mold provided therein with a molded article to be cured and showing the adaptation with the flask and mold of the separator and with the latter being in extended position relative to the flask,

Figure 4 is a cross sectional view of a closed flask containing a mold carrying a molded article to be cured and showing the adaptation of the separator with respect to the flask and mold,

Figure 5 is a fragmentary view in front elevation of the separator in non-active position,

Figure 6 is a section on line 6—6, Figure 5, and

Figure 7 is a vertical sectional view of the separator when in active position.

The flask, mold and molded article may be of any suitable form and those shown, are by way of example, for the purpose of illustrating the adaptation of the separator with respect to a flask and a mold. The separator is to be employed in connection with any form of flask and mold for which it is found applicable. If the flask is of the closable top type the separator will be used in connection with the upper section of the flask. If the flask is of the closable open bottom type the separator will be used in connection with the lower section of the flask.

The flask shown is indicated at 8 and it includes a lower section 9 having an inverted frusto-tapered chamber 10, a hollow open bottom and open top upper section 11 having its inner edge 12 of frusto-tapered contour which at its bottom registers with the top of the wall of chamber 10, and a closure or top plate 13. The flask 8 is shown by way of example as of semi-oval contour. The sections of the mold have registering openings, as is well known. The closure plate 13, as is well known, is formed with openings which are to align with the openings in said sections. As is well known holdfast means, not shown are employed for extension into the aligned openings for detachably connecting the flask sections and closure plate together. It is to be understood that the flask employed may be of any form for which the separator is applicable. The openings in the

- section 11 are shown and indicated at 14. The openings in section 9 and plate 13 are not shown.
- Within the flask 8 is an investing material 15 of any suitable type for the molded article 16 to be cured or processed. The investing material will be hereinafter termed a mold. The section 9 is first filled with the material 15, the molded article 16 then placed on the material 15 within section 9, the separator 17 is then positioned throughout against the inner edge of section 11 and the latter is then filled with the investing material. The flask 8, mold and separator 17 will then appear as shown in Figure 3, with the separator 17 interposed between the mold and edge 12 and extended from the section 9. The extended portion of the separator 17 is then bent outwardly to seat upon the top of section 11, after which the closure plate 13 is anchored in position.
- 20 The separator 17 includes an outer and inner section 18, 19 respectively arranged in abutting relation. The section 18 is of tape-like form and constructed from sheet asbestos. The length of section 18 corresponds to the length of edge 12.
- 25 The width of section 18 is less than that of section 19 and corresponds to the height of edge 12. The section 18 is to have one face thereof positioned throughout edge 12 in abutting relation to the latter. The other face of section 18 is to be positioned throughout against one face of section 19. The length of the latter corresponds to that of section 18. The other face of section 19 is to bear against the mold. The section 19 is of tape-like form. The section 19 is formed from thin sheet metal or any alloy which fuses above the fusing point of the temperature employed for the curing or processing of the molded article. Preferably the section 19 will be formed of sheet brass of the desired gauge possessing a readily bendable characteristic. It is to be understood that the length of section 18 may be greater than that of edge 12 whereby the ends of section 18 will overlap when section 12 is in position. It is also to be understood that the length of section 45 19 may be such as to have its ends overlap. The section 19 has its outer side marginal portion bent upon its outer face to provide a fold 20 having its free or lower lengthwise edge 21 spaced from the outer lengthwise edge 22 of section 18. The 50 distance between the lower edge 21 of fold 20 and the edge 22 of section 18 corresponds substantially to the thickness of fold 20. That portion of section 19 which extends outwardly from flask section 11 is indicated at 23 and includes the fold 20. When the portion 23 is bent outwardly to seat on mold section 11, the fold 20 not only seats on the top of section 11 but also on the edge 22 of section 18 (Figures 4 and 7). The extended portion 23 of the section 19 is formed with spaced slits 24 to facilitate the bending thereof. The slits 24 extend from the bend 25 to the edge 21 of the fold. The portion 23 constitutes a flange which is disposed at right angles to the remaining portion of the section 19.
- 65 After the completion of the curing or processing of the invested molded article, the plate 13 of the flask is removed and the portion 23 of the separator bent back away from the top of flask section 11. The mold is then held down by one hand and a knife or other suitable instrument inserted between the sections 9, 11 of the flask to pry the flask section 11 upwardly independent of the separator, as the latter does not adhere to the flask. The separator may now be peeled away 70 from the mold.

The separator may be used for the lower portion of the flask, where deemed advisable, using the same technic as for the upper portion of the flask. When the separator is used for the lower portion of the flask, the portion 23 is bent against the lower edge of the lower flask section, the latter being open at its top and bottom. The portion 23 is secured in bent position by the bottom plate of the flask. After curing the molded article the bottom plate is removed, the portion 23 of the separator is bent away from the lower section of the flask, and said lower section may be removed from the mold using a downward pressure on such section.

The section 18 is termed a flask section liner. The portion 23 of section 19 is termed a retainer for sections 18, 19. The remaining portion of section 19 is termed a mold protector.

The section 18 of the separator 17 not only constitutes a heat insulating medium, but as it is resilient it acts as a cushion between section 19 and the flask.

What I claim is:

1. In a mold-flask separator, a bendable composite body formed of an outer section of cushioning material and an inner section of thin metallic material abutting the inner face of the outer section, said sections being of tape-like form, said inner section including a portion extending from one of the lengthwise edges of the outer section capable of being bent outwardly to overlap said edge, said portion being formed throughout with spaced parallel slits disposed in transverse relation with respect to the remaining portion of the said section.

2. In a mold-flask separator, a thin bendable metallic member of tape-like form, said member being formed with an inwardly extending fold bearing against a part thereof, said fold and a part being extended outwardly substantially at right angles to the remaining portion of said member and being formed throughout with spaced slits.

3. In a mold-flask separator, a bendable composite body of tape-like form consisting of an outer section constituting a flask section lining possessing a cushioning characteristic and an inner section having a part thereof constituting a protector for the mold and its remaining part in the form of an outwardly directed flange providing a securing means therefor and for said outer section, said inner section being formed of thin metallic material and having the said remaining part thereof formed throughout with spaced slits and overlapping a lengthwise edge of said outer section.

4. In a mold-flask separator, a bendable composite structure formed of a strip of asbestos of tape-like form and a strip of thin metallic material of tape-like form positioned against and throughout one of the faces of the strip of asbestos, said strip of thin metallic material being of greater width than that of the asbestos strip and having a portion extended beyond one of the lengthwise edges of the strip of asbestos, said portion disposed at right angles to the remaining portion of said metallic strip and overlapping said edge, said portion being formed with inwardly extending spaced slits.

5. In a mold-flask separator, a bendable composite structure formed of a strip of asbestos of tape-like form and a strip of thin metallic material of tape-like form positioned against and throughout one of the faces of the strip of asbestos, said strip of thin metallic material being

of greater width than that of the asbestos strip and having a portion extended beyond one of the lengthwise edges of the strip of asbestos, said portion disposed at right angles to the remaining portion of said metallic strip and overlapping said edge, said portion being formed with inwardly extending spaced slits, the said portion including an inwardly extending slotted fold seated on said edge.

10 6. In a flask separator, a bendable composite

body consisting of an outer section of a material possessing insulating and cushioning characteristics and a metallic inner section abutting the inner face of the outer section, said sections being of tape-like form, said inner section including an outwardly directed slotted flange overlapping a lengthwise edge of the outer section, the said flange including a fold for seating on said edge.
